LEONHARDT UTTING, OF PHILADELPHIA, PENNSYLVANIA, ASSIGNOR TO
C. LIEBRICH, OF SAME PLACE.

Letters Patent No. 64,813, dated May 14, 1867.

IMPROVEMENT IN TRUNK-LOCKS.

The Schedule referred to in these Letters Patent and making part of the same.

TO ALL WHOM IT MAY CONCERN:

Be it known that I, LEONHARDT UTTING, of Philadelphia, Pennsylvania, have invented an Improvement in Trunk-Locks; and I do hereby declare the following to be a full, clear, and exact description of the same, reference being had to the accompanying drawing, and to the letters of reference marked thereon.

My invention consists of a spring-bolt and one or more tumblers, constructed, arranged, and operating in the peculiar manner fully described hereafter, so that a self-fastening device and an ordinary locking-bolt operated by a key may be combined in one lock, which affords greater security than the ordinary self-fastening locks usually attached to trunks.

In order to enable others skilled in the art to make and use my invention, I will now proceed to describe its construction and operation. On reference to the accompanying drawing, which forms a part of this specification—

Figure 1 is a vertical section of my improved trunk-lock; and

Figures 2, 3, and 4, interior face views of the same.

The red lines A in fig. 1 represent a portion of the front of a trunk, and B a portion of the lid. D is that part of the case of the lock which is let into the front of the trunk, and e the plate bearing against the same and secured to the case D by rivets passing through lugs a a. E is the bolt arranged to slide in guides on a plate, F, secured to the case, and acted on by a spring, b. The bolt has a projection, f, which, as seen in fig. 2, occupies a position across a vertical slot, d, in front of the case, and projects through a staple, h, which passes through the said slot and is secured to or forms a part of the hasp-plate G, the latter being hinged, as usual, to the plate H, secured to the lid B of the trunk. A tumbler, I, is hung to a pin on the bolt E, a notch in this tumbler fitting over a projection, i, on the plate F, when the bolt is in the position seen in fig. 2, the tumbler having a spring, j, bearing against the projection h on the said plate F. As seen in fig. 4, the bolt is in such a position that its projection f does not extend entirely across the slot d, so that on applying pressure to the hasp-plate G its staple h passing into the slot will bear against the bevelled portion x of the projection f of the bolt and force the latter back until the staple projects so far into the lock that the projection f can pass through it, when the bolt will spring back to its original position (fig. 4) and lock the trunk. Should it be required to draw the bolt back from this position and unlock the trunk, all that is necessary is to adjust the key to the pin m and turn it in the direction of the arrow, (fig. 4,) when the key will raise the tumbler, and, bearing against the projection n of the bolt, move the latter back, and thereby permit the withdrawal of the hasp, the latch recovering its original position on releasing the key. Should it be desirable, however, to fasten the hasp more securely, the key is turned in a contrary direction, thereby lifting the tumbler and moving the bolt to the position shown in fig. 2, so that its projection f shall extend entirely across the slot d of the case. In unlocking the trunk, the bolt must be operated by two movements of the key, the first movement causing the bolt to assume the position shown in fig. 4 and the second movement drawing the bolt back to the position shown in fig. 3.

It will be seen that the above lock possesses all the advantages of a self-latching device with the additional advantage of an ordinary lock requiring the aid of a key to operate the bolt. It will be evident to those familiar with the construction of locks that additional tumblers may be applied, if desired.

I claim as my invention, and desire to secure by Letters Patent—

The spring-bolt E and tumbler I, or its equivalent, constructed and operating substantially as described, so that a self-fastening device and an ordinary locking-bolt, operated by a key, may be combined in one lock.

In testimony whereof I have signed my name to this specification in the presence of two subscribing witnesses.

LEONHARDT UTTING.
